CLAIM

The ornamental design for a captioning communication device with volume control, as shown and described.

DESCRIPTION

The patent or application file contains at least one drawing executed in color. Copies of this patent or patent application publication with color drawings will be provided by the Office upon request and payment of the necessary fee.

FIG. 1 is a front view of a first embodiment of a captioning communication device with volume control, showing the light ring in a first state of use;

FIG. 2 is a front view thereof, shown in a second state of use.

FIG. 3 is a front view of a second embodiment of a captioning communication device with volume control, showing the light ring in a first state of use;

FIG. 4 is a front view thereof, shown in a second state of use;

FIG. 5 is a front view thereof, shown in a third state of use;

FIG. 6 is a front view thereof, shown in a fourth state of use;

FIG. 7 is a front view thereof, shown in a fifth state of use;

FIG. 8 is a front view thereof, shown in a sixth state of use;

FIG. 9 is a front view thereof, shown in a seventh state of use;

FIG. 10 is a front view of a third embodiment of a captioning communication device with volume control, showing the light ring in a first state of use;

FIG. 11 is a front view of the third embodiment thereof, shown in a second state of use;

FIG. 12 is a front view of the third embodiment thereof, shown in a third state of use;

FIG. 13 is a front view of the third embodiment thereof, shown in a fourth state of use;

FIG. 14 is a front view of the third embodiment thereof, shown in a fifth state of use;

FIG. 15 is a front view of the third embodiment thereof, shown in a sixth state of use; and,

FIG. 16 is a front view of the third embodiment thereof, shown in a seventh state of use.

(Continued)

In the drawings, the claimed design is defined by the solid lines and shaded surfaces; broken lines in FIGS. 1 through 16 immediately adjacent shaded surfaces represent boundaries of the claim and form no part thereof; and all other broken lines depict portions of the captioning communication device with a volume light ring that do not form any part of the claimed design.
